CLOSET

Henry James Newnes, London, England, assignor
to Austral Cabinet Company Limited, London,
England

Application January 10, 1938, Serial No. 184,286
In Great Britain January 9, 1937

7 Claims. (Cl. 4—115)

(Granted under the provisions of sec. 14, act of
March 2, 1927; 357 O. G. 5)

This invention relates to sanitary closets using chemical liquid as a solvent and deodorizer and of the kind in which a tank houses a receiving tray adapted to be raised from the liquid for use and returned thereto after use. Such a closet is generally provided with a hinged seat cover, in which case the seat cover is coupled with the mechanism for raising and lowering the tray so that the cover is opened as the tray is raised for use and closed as the tray is returned to the liquid.

The present invention is concerned with the provision of simple and effective means for controlling the rate of re-entry of the receiving tray into the liquid, and to this end consists in a sanitary closet of the kind referred to having the receiving tray carried by a plurality of axially movable bars extending up through the top of the tank; a cross member interconnecting said bars externally of the tank and movable as one with the bars and tray; a lever coupled to the cross member having a member cooperating with a track or guide; means being provided for retaining said member in engagement with the track or guide and friction means which may be either the same as the retaining means or separate therefrom for restraining its movement therealong.

In order that it may be clearly understood and more readily carried into effect, the invention is hereinafter described with reference to the accompanying diagrammatic drawings, in which:

Figure 1 is a side elevation of a sanitary closet according to the invention with the lid closed and the tank broken away to reveal the interior;

Figure 2 is a plan view corresponding to Figure 1;

Figure 3 is a side elevation similar to Figure 1 but showing the lid open; while

Figure 4 is a detail view of a drain plug with a shut-off device for use where the closet is used inside without an outlet to an earth pit.

Referring now to Figures 1 to 3 of the accompanying drawings, the tank 5 is intended to be filled with liquid approximately to the level indicated by the reference 6. The forward part of the top of the tank is open and is provided with a sanitary seat cover 7, over which there is hinged a lid 8 adapted to be opened and closed over the aperture in the seat 7, as required. Below the seat 7 and within the tank 5 is a receiving tray 9 of trough-like form, generally being of greater depth at the rear than at the front. The bottom of the tray is preferably of semicir-

cular section and is open at the back. The tray is carried on arms 10 which extend up rearwardly as a pair of bars 11 passing out through holes in the top of the tank through the guides 12 for cooperation with the cross member 13. The bars 11 can slide vertically in the guides 12, and consequently the cross member 13, the vertical bars 11 and the arms 10 provide a framework carrying the trough 9 which can move vertically so that the tray may be caused either to be lifted out of the liquid, or at least the base thereof immersed. Pivotally connected to the cross member 13 by means of a sliding collar 14 rotatable on the cross member is a lever 15, which is coupled to the lid by the eye-bracket 16, 15 whereby the lid may be raised or lowered by the lever 15. The eye-bracket 16 has the transverse rollers 17 and 18 engaging, respectively, above and below the lever 15 to provide for free movement of the lever in the eye-bracket. The lever extends rearwardly from the sliding collar 14, as indicated at 19, the downwardly-directed end of the extension being forked to receive a roller 20. The roller is adapted to move along a guide track when the lever 15 is operated to raise or lower the lid. The track is comprised by the upper part 21 and a lower spring member 22. The upper part 21 is of course spaced above the lower spring part 22, and the effect of the spring 22 is to grip the roller in order to prevent it running back too freely when the lever is moved downwards to lower the lid and cause the receiving tray 9 to re-enter the liquid. The upper part of the track conveniently will extend down as the vertical arm 23 adapted to be attached to the back of the tank, while the other end thereof can be turned down, as indicated at 24, to meet the front end of the spring member 22 so that the two parts of the track can be bolted together on the top of the tank.

In Figure 3 the spring member 22 of the track is shown in the position which it assumes when the roller is at the front end of the track, as it is with the seat in the raised condition.

A closet as hereinbefore described may be made up in a simple and light form so that it can be carried away for emptying, or maybe for transportation, and to facilitate lifting it the handles 25 may be provided.

Preferably, such a closet as above described will be installed over an earth pit, and will have a drain plug including an overflow device associated with it. The drain plug will preferably engage in a boss of rubber, specially treated to re-

sist the action of the caustic materials of the liquid usually employed in chemical closets.

Where the closet is intended to be used without an earth pit, for example in a caravan or perhaps in a boat, the drain plug will preferably include means for shutting off the overflow, and a plug with such shut-off means is illustrated in Figure 4. The plug itself, indicated by the reference numeral 26, has a central aperture through it and has upstanding from it the outer tube 27 with an aperture 28. Within the tube 27 is an inner tube 29 having an aperture 30, which when ordinarily operating to provide an overflow will be in register with the aperture 28. When it is required to shut off the overflow, as it may be when the device is used without an earth pit, the inner tube 29 may be turned by means of the knob 31 until the aperture 30 no longer registers with the aperture 28. The plug 26 will when properly engaged in the outlet be held sufficiently tightly to enable the inner tube 29 to be turned without turning the plug. In order to define the limits of angular movement, and to position the aperture 30 properly 25 with respect to the aperture 28, a grub screw 32 will be engaged in the inner tube 29, the outer tube 27 being slotted, as indicated at 33, to permit movement of the grub screw. The guard tube 34 with its apertures, such as 35, is provided to 30 prevent undissolved paper or solid matter from fouling the overflow. In order to provide access to the handle 31 for shutting off the overflow, and also for removing the drain plug as a whole, there will be an aperture in the top of the tank, for 35 which the cover 36 will be provided.

The lid 3, although not absolutely necessary, is obviously desirable, but where it is dispensed with the tray may be caused to rise and fall by means of a lever corresponding to the lever 15, which 40 may be considerably shorter than where it has to engage the lid, the rest of the structure remaining substantially the same with the exception of the means for coupling the handle 15 to the lid.

Again, in cases where the closet is to be used without an earth pit, as it would be in a caravan or in a boat, the tank 5 may be lined with a separate container intended to be lifted out for emptying, but in such a case it would not be desirable 50 to include an overflow and the inner container will need to be emptied out from time to time before it gets too full.

It will be apparent that numerous arrangements may be provided for introducing the necessary friction between the roller and its guides; for example, the roller may be connected to the seat or a convenient fixed anchorage on the tank by means of a spring, so placed as to tend to draw the lever inner end into engagement with the guide 60 during downward swinging movement of said lever. Similarly, a friction member may be included in the hub of the roller, which then need not be gripped by spaced guide members but merely located by them. Again, it may suffice 65 to provide near the rear end of the track upon which the roller bears a projection extending forwardly over that member but spaced therefrom so that the roller is pressed into frictional contact with the track to be gripped between the 70 projection and the track at least towards the rear end of the track.

What I claim is:

1. A sanitary closet of the class described including a tank having an opening in the top thereof, a receiving tray in said tank under the 75

opening, a plurality of axially movable bars carrying the receiving tray and having end portions extending up through the tank, a cross member interconnecting said bars externally of the tank and movable with the bars and tray, a guide comprising spaced members extending longitudinally behind said seat, certain of said spaced members being resilient, and a lever having an inner end engaged between the spaced members of said guide so as to be movable therebetween along the length of the guide and being pivotable with respect thereto, said lever being operatively associated with said cross member for raising and lowering the receiving tray, said resilient member serving to cooperate with the other member 10 of the guide to grip the end of the lever engaged thereby and restrain its movement therealong. 15

2. A sanitary closet of the class described including a tank with an opening in the top thereof, a receiving tray in said tank, a plurality of axially movable bars carrying the tray and having end portions extending up through the tank, a cross bar interconnecting said bars externally of the tank and movable with the bars and tray, a lever operatively associated with said cross bar 20 for raising and lowering the receiving tray and having a roller, a guide extending longitudinally at the rear of the seat and comprising spaced members, certain thereof being resilient, said members engaging the roller whereby said roller 25 will be retained to travel along the length of the guide and restrained against movement therealong. 30

3. In a sanitary closet of the class described, a tank having a top formed with an opening, waste receiving means in the tank under the opening, a plurality of axially movable bars having portions thereof extending through the tank, said bars carrying the waste receiving means, a cross member interconnecting said bars and movable therewith, a guide extending longitudinally behind the seat and comprising an upper part and a resilient lower spring member spaced below said upper part, and a lever having a roller at its inner end, said roller being disposed between the 40 members of the guide and being resiliently engaged by the lower spring member, said roller and inner end of the lever being restricted to sliding movement along the length of the guide and said lever being pivotally mounted in said 45 guide, said lever being operatively connected with the cross member and being shiftable for raising and lowering the waste receiving means. 50

4. A sanitary closet of the class described, including a tank having an opening in the top thereof, a receiving tray in said tank under the opening, a plurality of axially movable bars having portions extending up through said tank, said bars carrying the receiving tray, a cross member interconnecting said bars externally of the tank and movable with the bars and tray, a guide extending longitudinally behind said seat, a lever having its inner end connected with said guide for movement longitudinally therealong as the lever is swung in a substantially vertical 65 plane, said lever being operatively associated with said cross member for raising and lowering the receiving tray, and friction means for restraining movement of the inner end of the lever along the guide. 70

5. A sanitary closet of the class described, including a tank having an opening in the top thereof, a hinged closure lid for said opening, a receiving tray located in said tank under the opening, a plurality of axially movable bars 75

- mounting the tray and having end portions extending up through the tank, a cross member interconnecting said bars externally of the tank and movable with the bars and tray, a guide comprising spaced members extending longitudinally behind said seat, certain of said spaced members being resilient, and a lever having an inner end engaged between the spaced members of said guide so as to be movable therebetween
- 5 10 15 20 25 30
- 10 along the length of the guide and being swingable in a substantially vertical plane with respect thereto, said lever being operatively associated with said cross member for raising and lowering the receiving tray, said resilient member serving to cooperate with another member of the guide to grip the end of the lever engaged thereby and restrain its movement therealong.
- 15 20 25 30
6. A sanitary closet of the class described, including a tank having an opening in the top thereof and having an outlet plug associated with the tank, an overflow means associated with said outlet plug, a receiving tray located in said tank under the opening, a plurality of axially movable bars mounting the tray and extending up through said tank, a cross member interconnecting said bars externally of the tank and movable with the bars and tray, a guide comprising spaced members extending longitudinally behind said seat, certain of said spaced members being resilient, and a lever having an inner end engaged between the spaced members of said guide so as
- 10 15 20 25 30
- to be movable therebetween along the length of the guide and being swingable in a substantially vertical plane with respect thereto, said lever being operatively associated with said cross member for raising and lowering the receiving tray, said 5 resilient member serving to cooperate with another member of the guide to grip the end of the lever engaged thereby and restrain its movement therealong.
7. In a sanitary closet of the class described, a tank having a top formed with an opening, waste receiving means in the tank beneath the opening, axially movable bars having portions thereof extending through the tank, said bars carrying the waste receiving means, a cross member interconnecting the bars and movable therewith, a guide extending longitudinally behind the seat and comprising an upper part and a resilient lower spring member spaced below the upper part, a lever having a roller at its inner end, said roller and inner end of the lever being restricted to sliding movement along the length of the guide and said lever being pivotally mounted in the guide, said lever being operatively connected with the cross member and being shiftable for receiving and lowering the waste receiving means, a lid hingedly connected with the top of the tank, and means operatively connecting the lid with the lever, said means including an I-bracket engageable with the lever.
- 10 15 20 25 30

HENRY JAMES NEWNES.
